UNITED STATES PATENT OFFICE.

HERMAN ROSENGARD AND ALECK GOLDBERG, OF CHICAGO, ILLINOIS.

DESIGN FOR A CABINET.

No. 39,860.

Specification for Design.

Patented March 2, 1909.

Application filed December 26, 1908. Serial No. 469,495. Term of patent 3½ years.

To all whom it may concern:

Be it known that we, HERMAN ROSENGARD and ALECK GOLDBERG, both citizens of the United States, residing at Chicago, in the county of Cook and State of Illinois, have invented a certain new, original, and ornamental Design for Cabinets, of which the following is a specification, reference being had to the accompanying drawing, forming a part thereof.

The figure on the drawing is a perspective view of a cabinet showing our new design.

We claim:

The ornamental design for a cabinet, as shown.

HERMAN ROSENGARD.
ALECK GOLDBERG.

Witnesses:

JAMES R. OFFIELD,
M. E. ADAMS.
